Patented Dec. 13, 1921.

UNITED STATES PATENT OFFICE.

WILLIAM B. LOEWENBERG, OF MARION, INDIANA.

BASKET.

1,399,974.

Specification of Letters Patent. Patented Dec. 13, 1921.

Application filed March 5, 1921. Serial No. 449,820.

To all whom it may concern:

Be it known that I, WILLIAM B. LOEWENBERG, a citizen of the United States, residing at Marion, in the county of Grant and 5 State of Indiana, have invented certain new and useful Improvements in Baskets; and I do declare the following to be a full, clear, and exact description of the invention, such as will enable others skilled in the art to 10 which it appertains to make and use the same.

My invention relates to improvements in split or market baskets of the type having a single arched handle. These baskets as 15 now commonly constructed, cannot be nested and even though they may be connected with each other in bunches, a great deal of waste space necessarily exists when shipping, but nevertheless the freight rates are 20 the same, as if all of the car capacity were used. My invention aims to overcome this difficulty by the provision of a foldable handle which may be swung downwardly to permit a number of the baskets to be nested 25 for shipment. Folding handles have heretofore been devised for this purpose as seen for instance in my own U. S. Patent No. 1,354,115 of September 28, 1920. In this patented device however, as well as in the 30 other devices to which I refer, the handle is not connected with the basket as rigidly as desirable when raised for use, and my present invention has for its object to overcome this difficulty in an effective manner.

35 With the foregoing in view, the invention resides in the novel construction and arrangement of parts hereinafter described and claimed, the descriptive matter being supplemented by the accompanying drawings.

40 Figure 1 is a side elevation of a basket constructed in accordance with my invention.

Fig. 2 is an enlarged vertical transverse section as indicated by line 2—2 of Fig. 1.

Fig. 3 is a detail horizontal sectional view as indicated by line 3—3 of Fig. 2.

Fig. 4 is a fragmentary perspective view showing the handle in operative position.

50 Fig. 5 is a duplicate of Fig. 4 with the exception that it illustrates the handle in condition for folding.

55 In the drawings above briefly described, the numeral 1 designates a basket whose general formation of wooden splints, is quite common, although a number of im-

provements have been made. The rim of the basket is formed of outer and inner bands 2 and 3 secured together at intervals on opposite sides of the usual vertical 60 splints. At the center of the basket, two relatively thin splints 4 and a thicker splint 5 extend across the bottom of the basket and up along the sides thereof, with their upper ends received between the bands 2 and 3. 65 Received between the vertical portions of the splints 4 and located one at each side of the basket, are two vertical reinforcing strips 6 which are relatively stiff. These strips project above the basket rim as indicated at 7 and due to the fact that the sides of the basket diverge upwardly, said 70 projecting strip ends are inclined to some extent. To secure the upper end portions of the strips 6 in place, a number of nails 75 8 are driven through the rim of the basket, through said strips, and through the splints 4 and 5, said nails being clenched in the usual way.

Straddling the basket, is an arched handle 9 whose lower ends are pivoted by means of bolts 10 to the sides of the basket at points preferably near its vertical center, although this is not absolutely essential. The bolts 10 pass through the ends of the 85 handle 9, through the splints 4 and 5, through the reinforcing strips 6, and preferably through at least one of the horizontal splints 11 of which the basket is partially constructed. Due to the inclination 90 of the projecting strip ends 7 and the curvature of the handle 9, said strip ends converge upwardly with the handle as clearly shown in Figs. 2 and 5 and I make use of this convergence to frictionally bind a pair 95 of metal sleeves 12 in operative position to hold the handle 9 upright for use, said sleeves being slidable on the handle and being tapered for snug contact with the strip ends 7 and the adjacent portions of 100 the handle as shown in Figs. 2 and 4.

By the construction shown and described or its mechanical equivalent, a basket is provided which is not only advantageous on account of having a folding handle, but on 105 account of the fact that it is effectively reinforced by the strips 6 and their association with the vertical splints. In addition to performing this reinforcing function however it will be seen that the parts in 110 question form a durable construction to which the handle may be pivoted without

danger of injuring the basket, even when it is heavily loaded. Also the upper ends of the strips 6 coat with the sleeves 12 in securing the handle in vertical position, while 5 permitting it to be swung downwardly whenever required. The baskets may be shipped in nested relation with their handles swung downwardly as indicated in dotted lines in Fig. 1 and a great deal of 10 space is therefore saved in freight cars or other transporting mediums, which means a great financial saving to the manufacturer or the dealer, as the case may be, and ultimately to the public. When received, 15 the handles of the baskets may be easily swung upwardly for use and held by the sleeves 12 and if it is desired to at all times retain said handles in an upright position, tacks may be driven above the sleeves as indicated by the dotted lines in Fig. 2, or below 20 said sleeve into the rim of the basket. However, in most cases, it will be desired to omit the tacks so that the sleeves may be raised whenever it is required to fold the 25 handle, for instance to save store room, especially in large cities.

The device is simple and inexpensive, yet is highly efficient and in every way desirable and since excellent results have been 30 obtained from the details disclosed, I prefer to follow these details. However, within the scope of the invention as claimed, numerous minor changes may be made to embody the improved features in forms other 35 than those shown.

I claim:

1. The combination with a basket, of a pair of reinforcing strips secured to the sides of said basket and extending above the 40 same, an arched handle pivoted to said reinforcing strips at points spaced downwardly from their upper ends, and means for connecting the handle with said projecting strip ends to hold it in upright position.

2. The combination with a basket, of a pair of reinforcing strips secured to the sides of said basket and extending above the same, an arched handle pivoted to said 50 reinforcing strips at points spaced downwardly from their upper ends, and sleeves slidable on said handle and adapted to pass around the upwardly projecting ends of said reinforcing strips to rigidly hold said handle in upright position.

3. The combination with a basket having

upwardly diverging sides, of a pair of reinforcing strips secured to said sides and projecting above the same, an arched handle pivoted to said strips at the outer sides of 60 the basket and converging upwardly with said projecting strip ends, and tapered sleeves slidable on said handle and adapted to wedge over said projecting strip ends to hold the handle in upright position. 65

4. A splint basket having a rim formed of inner and outer bands, and provided at its center with a plurality of superposed splints extending across the bottom of the basket and up its sides with their free ends anchored between said bands of the rim, relatively stiff vertical reinforcing strips secured between the vertical portions of said splints and projecting above the basket rim, an arched handle straddling the basket, fasteners passing through said handle and through the aforesaid splints and reinforcing strips to pivotally connect the handle to the basket, and means for connecting said handle with said projecting strip ends above its pivots, whereby to hold the handle in upright position. 70

5. A splint basket having a rim formed of inner and outer bands, and provided at its center with a plurality of superposed splints extending across the bottom of the basket and up its sides with their free ends anchored between said bands of the rim, relatively stiff vertical reinforcing strips secured between the vertical portions of said 75 splints and projecting above the basket rim, an arched handle straddling the basket, fasteners passing through said handle and through the aforesaid splints and reinforcing strips to pivotally connect the handle to the basket, and sleeves slidable on said handle and adapted to pass around the upwardly projecting ends of said reinforcing strips to rigidly hold said handle in upright position. 80

6. The combination with a basket, of lugs rising from the sides thereof, an arched handle straddling the basket in the same transverse plane with said lugs and pivotally connected with said basket below said 95 lugs, said lugs converging upwardly with the handle, and tapered sleeves slidable on the handle to wedge over said lugs and hold the handle in upright position. 100

In testimony whereof I have hereunto set my hand.

WILLIAM B. LOEWENBERG.
